CLAIM

The ornamental design for a deadbolt faceplate with LED strip having animated illumination, as shown and described.

DESCRIPTION

The patent or application file contains at least one drawing executed in color. Copies of this patent or patent application with color drawing(s) will be provided by the Office upon request and payment of the necessary fee.

FIG. 1 is the first image in the sequence for a deadbolt faceplate with LED strip having animated illumination showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is the nineteenth image thereof;

FIG. 20 is the twentieth image thereof; and,

FIG. 21 is the twenty-first image thereof.

The appearance of the deadbolt faceplate with LED strip having animated illumination sequentially transitions between the images shown in FIGS. 1-21. The process or period in which one image transitions to another forms no part of the claimed design. The broken line showing of the deadbolt faceplate illustrates environmental structure and forms no part of the claimed design.
